(57) **CLAIM**

The ornamental design for an outboard motor machine, as shown and described.

DESCRIPTION

FIG. 1 is a right perspective view of an outboard motor machine showing our new design;

FIG. 2 is a left perspective view thereof;

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The broken line showing portions of an outboard motor machine is included for the purpose of illustrating environmental structure and forms no part of the claimed design.
